DESIGN FOR AN AIRPLANE, OR THE LIKE

Henry Silverstein, Brooklyn, N. Y.

Application November 30, 1938, Serial No. 81,479

Term of patent 14 years

To all whom it may concern:

Be it known that I, Henry Silverstein, a citizen of the United States, residing at No. 1565 St. Marks Avenue, Brooklyn, in the county of Kings and State of New York, have invented a new, original, and ornamental Design for an Airplane, or the like, of which the following is a specification, reference being had to the accompanying drawing, forming part thereof.

In the drawing:

Fig. 1 is a rear perspective view of an airplane or the like, showing my new design;

Fig. 2 is a view taken along the section line 2—2 in Fig. 1, looking in the direction of the arrows, with certain parts accordingly being shown in section and others in side elevation; and

Fig. 3 is a top plan view of the airplane, or the like, which is shown in Fig. 1.

I claim:

The ornamental design for an airplane or the like, as shown.

HENRY SILVERSTEIN.
